ELECTRIC DEVICES FOR LUMINOUS ADVERTISING

Fábio Teixeira de Carvalho, São Paulo, Brazil

Application February 19, 1957, Serial No. 641,180

2 Claims. (Cl. 315—316)

The present invention relates to an improved electric device suitable for luminous advertising and represents an innovation in the field of advertising activity because the construction of said improved device gives to the spectator some visual effects unknown up to the present time. It should be noted that said improved apparatus is able continuously to exhibit several movable representations in colors changed automatically, which up to this day has not been accomplished. The following description will make clear all the essential details of the invention.

The improved apparatus substantially consists of a lamp-supporting panel connected to an electric current-supply circuit, in which panel is housed a controlling device which includes a mercury electrode conveniently spaced from the upper surface of a support of dielectric material, this dielectric support carrying a plurality of contacts operatively connected to the mentioned electrode.

A sliding sheet of dielectric material is provided between said electrode and said plurality of contacts; this sliding sheet has preferably the form of a removable endless tape of paper, cellulose or the like, which is provided with a conveniently arranged plurality of holes. Said holes, on passing between the electrode and the plurality of contacts above mentioned, will permit the electric circuit to be established for certain lamps on the panel, whose light will form the desired symbol or figure.

In this way there is ensured and facilitated the alternative lighting or extinguishing of one or several groups of electric lamps of at least one color, which operate when connected to the electric current-supply circuit closed by means of the holes provided in the cited sliding sheet. This sliding sheet is conveniently protected against friction during its movement.

As above stated, it is clear that the improved apparatus can produce a wide variety of combinations of figures and colors, even when it is of relatively limited dimensions. Other details of the invention will be evidenced by the following description of one of its preferred embodiments.

In order to facilitate the understanding of the subject matter of the present invention, there is represented in the appended drawing, by way of non-limitative example, one preferred embodiment. In the drawing:

Fig. 1 is a partial view of the apparatus, showing the part of the device in which is housed the controlling device, the supporting arms and the guide member for the perforated sheet;

Fig. 2 is a partial side view of the same apparatus showing a longitudinal section;

Fig. 3 is a partial front view of the lamp-supporting panel;

Fig. 4 is a plan partial view of a part of the sliding sheet, showing groups of holes forming figures;

Fig. 5 is a partial front view of the luminous panel with figures formed by two combined colors, which were obtained by sliding the part of the sheet represented in Fig. 4;

Fig. 6 is a plan partial view of the contact-supporting

2

sheet, these contacts being grouped in accordance with the number of colors employed and connected to the associated groups of lamps;

Fig. 7 is a view similar to Fig. 1 but showing the perforated tape operatively supported on the apparatus; and

Fig. 8 is a fragmentary cross-sectional view, on a larger scale, taken on the line VIII—VIII of Fig. 7.

As shown in the drawing, the improved apparatus comprises a panel or screen 1 which supports a plurality of electric lamps 2 connected to at least one electric current-supply circuit comprising a power source 3, shown as a transformer, and a controlling device; this controlling device comprises at least one suitable electrode 4 conveniently spaced from the surface of a dielectric supporting body 5 which is provided with a plurality of contacts 6, operatively connected to the electrode 4. Between this electrode and the plurality of contacts is disposed a movable thin strip 7 of dielectric material which has preferably the form of a continuous tape and is guided by suitable means as illustrated in Fig. 7. This tape has a plurality of holes 8 through which can pass the contact pins 6 to come into contact with the electrode 4 during the movement of the tape 7.

The electrode 4 preferably comprises a coating of mercury on a steel plate 10. The electrode is connected by means of the lead 11 to one terminal of the secondary transformer winding 12 whose second terminal is connected to ground by means of a lead 13 having branches which extend to the permanent contacts of the lamps 2, as can be seen in Fig. 2. The contacts 6 are connected by means of leads 14 to the lamps 2 on the panel 1 as seen in Figs. 6 and 8.

The lamps 2 are arrayed on the panel 1 in groups of at least two lamps of different colors arranged in cup-like recesses 15.

The contacts 6 operatively connected to the electrode 4 and mounted on the support 5 are longitudinally divided into at least two groups or banks "a" and "b" each corresponding to one color.

Fig. 10 The dielectric perforated sliding tape 7 between the electrode 4 and the contacts 6 can be made of paper, cellulose, or the like and is suitably driven and guided. The holes 8 are longitudinally divided into at least two groups "c" and "d" each corresponding to one color.

The guiding means for the sliding tape 7 are represented by main rollers 16 and secondary rollers 17 which bear on suitable supports 18 provided in a frame 19 conveniently disposed. Besides, there are provided a tensioning device 20 a clutch and speed-changing device 22 and drive means 21 for causing motion.

After the holes have been made in the tape 7 in accordance with the symbols or figures which are intended to be shown, this tape is put on the rollers 16 and 17 and passed between the electrode 4 and the contacts 6 so that, for instance, the group "c" of holes, which correspond to one color, coincide with the group "a" of contacts 6, which are connected by means of wire 14 to the lamps of the same color; and the group "d" of holes 8, which correspond to the other color, coincides with the group "b" of contacts 6, which are connected by means of wires 14 to the lamps of the other color. Notwithstanding the description, being made of the case in which only two colors are used, it is to be understood that the invention is not limited to this case, because if it is desired to employ more than two colors, it is sufficient to make each group of lamps with more than two lamps and to provide more than two groups of contacts and perforations in the sliding sheet. If, for instance, it is desired to use four different colors, each group of lamps must have four lamps, the plurality of contacts must be divided into four longitudinally spaced groups and the sliding tape must

also be provided with four longitudinally spaced groups of holes, each group of holes and contacts controlling the operation of the lamps of one color.

The supply circuit of each lamp 2 will be closed when a hole 8 of the sliding tape 7 passes over the corresponding contact 6, while the supply circuits of the other lamps 2 will remain open during the passage of the unperforated parts of the sliding tape 7 over their corresponding contacts 6. In this way, by suitable combination of holes in the sliding tape, the various colors may be conveniently combined and the figures formed on the panel will move at a speed which corresponds to the speed of the displacement of the sliding tape 7 between the electrode 4 and the plurality of contacts 6.

It is obvious that some constructional details may be modified in relation to the specifically described embodiment of the invention without departing from its spirit and scope, as defined in the appended claims.

What I claim is:

1. A luminous display device comprising a first set of lamps of one color and a second set of lamps of another color, the lamps of said first set being closely juxtaposed with respective lamps of said second set, a first and a second bank of electrodes constituting two parallel arrays, counter-electrode means substantially coextensive with both of said arrays and positioned adjacent the electrodes thereof, an elongated insulating member separating said counter-electrode means from said banks of electrodes, said member being longitudinally divided into two zones respectively registering with said arrays and being provided with discontinuities in its insulation adapted to enable the establishment of electrical contact between said counter-electrode means and respective electrodes of each of said banks, circuit means for selectively energizing the lamps of said first set through respective electrodes of said first bank and the lamps of said second set through respective electrodes of said second bank by way of said discontinuities, and drive means for displacing said member between said banks and said counter-electrode means in a manner maintaining said zones in alignment with the respective electrode banks, the discontinuities in each zone representing a respective color component of a multicolor pattern displayed by said lamps in progressive motion upon the displacement of said member.

2. A luminous display device comprising a panel with a plurality of light sources arranged in a plurality of parallel rows, each of said light sources including a pair of closely juxtaposed lamps of respectively a first and a second color, a first and a second bank of electrodes arranged in a plurality of parallel rows constituting two arrays, the number of rows in each array equaling the number of rows of said light sources, counter-electrode means extending across all of said rows of said banks adjacent the electrodes thereof, an elongated insulating member separating said counter-electrode means from said banks of electrodes, said member extending with its major dimension parallel to said rows of electrodes and being longitudinally divided into two zones respectively registering with said arrays, said member being provided with discontinuities in its insulation adapted to enable the establishment of electrical contact between said counter-electrode means and respective electrodes of each of said banks, circuit means for selectively energizing the lamps of said first color through respective electrodes of said first bank and the lamps of said second color through respective electrodes of said second bank by way of said discontinuities, and drive means for longitudinally displacing said member between said banks and said counter-electrode means, the discontinuities in each zone representing a respective color component of a multicolor pattern displayed by said lamps in progressive motion upon the displacement of said member.
